FLUID DISCHARGE APPARATUS

Thomas C. Shiels, Toronto, Ontario, Canada, assignor to Elias Rogers Company Limited, Toronto, Ontario, Canada

Application March 19, 1937, Serial No. 131,873

5 Claims. (Cl. 299—58)

This invention relates to apparatus in which the flow of a fluid to and through an outlet is liable to be interfered with by low temperature and is described as adapted to apparatus in which 5 the fluid flowing is a heavy oil but which may be used with other fluids.

Apparatus is now in use in which hot oil is sprayed from an outlet nozzle to lay the dust as coal is fed down a chute to a container.

10 As the oil is cut off adjacent the outlet when no coal is being fed and frequently for considerable periods of time, it is often found that the heavy oil used will, in cold weather, so increase in viscosity adjacent the outlet that it will not 15 spray satisfactorily but flow in a thick stream.

This is unsatisfactory and also wasteful, and my object is to devise means for maintaining the oil in a sprayable condition at the nozzle at all 20 times, particularly during cold weather and when the flow at the nozzle is cut off.

I attain my object by means which may be briefly described as follows.

The oil is caused to flow under pressure through a supply conduit and is maintained at a suitable 25 temperature for spraying. A branch pipe leads from the said conduit and is provided with an outlet nozzle or nozzles. A pipe, forming a shunt circuit, is connected with the supply conduit at each side of the connection of the branch pipe and 30 heat exchange means is located in the shunt conduit adapted to transfer heat to the outlet nozzle. As long therefore as heated oil is flowing in the supply conduit the oil in the branch pipe and outlet will be maintained substantially at the same 35 temperature as that in the supply conduit.

The invention is hereinafter more fully described and is illustrated in the accompanying drawing in which

Fig. 1 is a diagram showing the general arrangement of the spraying system;

Fig. 2 a plan view on a larger scale of the arrangement of the spraying apparatus; and

Fig. 3 a section on the line 3—3 in Fig. 2.

In the drawing like numerals of reference indicate corresponding parts in the different figures.

Referring to Fig. 1 of the drawing, 1 is the supply conduit in which oil is circulated by means of the pump 10. A pressure relief valve 9 is provided in this conduit adjacent the suction side 50 of the pump. Any excess oil not used from the supply conduit at a predetermined pressure passes back to the pump. The pump draws its supply of fresh oil from the tank 8 through the pipe 13 which is connected with the conduit 1 between the pump and the pressure relief valve. A heater 55

11, preferably electric, is included in the conduit. In practice various refinements are included in the circulating and heating system but as both the general arrangement and details are old in the art these details are neither shown nor described. 5

Referring particularly to Figs. 2 and 3, it will be seen that the supply conduit 1 has connected thereto at spaced points a shunt conduit 1a. The part 1b of the conduit 1 between the points 10 of connection of the shunt conduit is provided with means for restricting the flow of oil therethrough to ensure a flow through the shunt conduit. This may be done by restricting the cross sectional area of part or whole of the part 1b. 15 I show, for example, the part 1b as a pipe of smaller bore than that of the pipe forming the shunt circuit. A valve 12 might also be used instead of or in addition to the permanent restriction of the bore of the part 1b. 20

From the part 1b of the supply conduit extends the branch pipe 2 supplying oil to one or more spray nozzles 6. A valve 7 is provided in this branch pipe by means of which the supply to the nozzles may be cut off at will. 25

The connection between the branch pipe and the nozzles is formed by the chamber 5 formed in the metal block 3 which forms heat exchange means included in the shunt circuit 1a for heating the nozzles. This block, for the stated purpose, is formed with a chamber 4 included in the shunt circuit, which chamber is separated from the chamber 5 by a metal wall through which heat from the oil in the shunt circuit passes to heat the oil in the chamber 5. This is particularly important if a spray nozzle be employed such as shown in co-pending application No. 105,208 filed October 12, 1936 in which there is a check valve included in the spray nozzle and oil is held in the chamber 5 when the valve 7 is closed 40 or in cases where the nozzle is arranged to spray upwardly in which case oil is also pocketed in the chamber 5. The nozzles 6 are also directly heated by conduction from the block 3 into which they are screwed. 45

The branch pipe 2 is also heated by conduction from the block 3 and also by conduction from the part 1b of the supply conduit.

Thus, when the valve 7 is closed and no oil is flowing to the nozzles, the temperature of the 50 branch pipe 1a, the valve 7 and the nozzles 6 is kept at such a height as to prevent the oil congealing therein, since at all times hot oil is being circulated in the supply conduit 1, 1b and the shunt conduit 1a. Thus the production of a 55

proper spray from the nozzles is ensured at all times and waste is prevented.

Any type of outlet may be employed, as also any known form of heat exchange means. Various changes might also be made in the details of construction to fit the apparatus for use with fluids other than oil and which would fall within the scope of my invention.

What I claim as my invention is:

- 10 1. In fluid discharge apparatus, the combination of a supply conduit; means for causing a flow of fluid through said conduit; a branch pipe leading from said conduit and provided with an outlet nozzle; a shunt conduit connected with the supply conduit at each side of the connection of the branch pipe and through which part of the fluid passes; and heat exchange means located in the shunt conduit and adapted to transfer heat from the shunted fluid to the outlet nozzle.
- 15 2. In fluid discharge apparatus, the combination of a supply conduit; means for causing a flow of fluid through said conduit; a branch pipe leading from said conduit and provided with an outlet nozzle; a shunt conduit connected with the supply conduit at each side of the connection of the branch pipe and through which part of the fluid passes; heat exchange means located in the shunt conduit and adapted to transfer heat from the shunted fluid to the outlet nozzle; and a cut-off valve located in the branch pipe.
- 20 3. In fluid discharge apparatus, the combination of a supply conduit, means for causing a flow of fluid through said conduit; a branch pipe leading from said conduit and provided with an outlet nozzle; a shunt conduit connected with the supply conduit at each side of the connection of the branch pipe and through which part of the fluid passes; and heat exchange means located in the shunt conduit and adapted to transfer heat from the shunted fluid to the outlet nozzle; and a cut-off valve located in the branch pipe.
- 25
- 30

let nozzle; a shunt conduit connected with the supply conduit at each side of the connection of the branch pipe and through which part of the fluid passes; a restriction in the supply conduit between the points of connection of the shunt conduit to ensure a part of the fluid flow passing through the shunt circuit; and heat exchange means located in the shunt conduit and adapted to transfer heat from the shunted fluid to the outlet nozzle.

4. In fluid discharge apparatus, the combination of a supply conduit; means for causing a flow of fluid through said conduit; a branch pipe leading from said conduit and provided with an outlet nozzle; a shunt conduit connected with the supply conduit at each side of the connection of the branch pipe and through which part of the fluid passes; a restriction in the supply conduit between the points of connection of the shunt conduit to ensure a part of the fluid flow passing through the shunt conduit; heat exchange means located in the shunt conduit and adapted to transfer heat from the shunted fluid to the outlet nozzle; and a cut-off valve located in the branch pipe.

5. Oil spraying apparatus as set forth in claim 1 in which the heat exchange apparatus comprises a metal block having a chamber therein forming part of the shunt conduit and a second chamber therein forming a part of the branch pipe, the two chambers being in heat exchange relationship.

THOMAS C. SHIELS.
